MATHEMATICAL INSTRUMENT

Frederic L. Graham, New York, N. Y.

Application November 18, 1938, Serial No. 241,175

11 Claims. (Cl. 33—75)

This invention relates to mathematical instruments and is herein disclosed in some detail as embodied in a navigating device in the form of a velocity trianglegraph and flight calculator suitable for airplane pilots.

One of the serious problems facing pilots arises from the need to allow for the force and direction of the wind. According to the present invention the necessary corrections can be arrived at by 10 mechanical operations which give a direct numerical reading to the person manipulating them without any computing whatever.

In one form the device enables the pilot to mechanically ascertain the force and direction of the wind if he can observe the track and ground speed, and thus avoid all the time and attention and knowledge needed to solve the so-called triangle of velocities.

The instrument of the present invention is
20 adapted to be easily held in the hand, requires
no pencil or other temporary marking, and is
completely self-contained. Moreover, it is rugged
in construction, capable of being cheaply built,
requires no mental arithmetic and has few mov-
25 ing parts.

Other features and advantages will hereinafter appear.

In the accompanying drawing,

Figure 1 is a face of an instrument embodying the invention, parts being partly broken away and some rulings only partly shown.

Figure 2 is a sectional view on the broken line 2-2 of Figure 1.

In the form shown, the instrument includes a built up body 3 having in effect a rabbeted central circle cut out of it so that the ledge 4 of the rabbet accommodates the projecting annular edge 5 of built up annular azimuth circle 10 which is graduated in degrees or aliquot numbers of degrees.

The azimuth circle 10 also includes an internal annular projection 6, in which lies the external rabbet 7 of a built up disc 13 forming a wind grid ruled in two directions at right angles to each other. In the form shown alternate ruled lines are broken lines, thus facilitating rapid following by the eye.

On a pivot 15 at one side of the body 3 are shown four pointers 14, 16, 17, 18 which extend across the faces of the wind grid 13 and azimuth circle 10, and are prolonged so as to catch under an arcuate overhang 8.

In the form shown two of the pointers 14 and 16 are so curved adjacent the pivot 15 that their facing edges form radii from the pivot 15, and

are graduated in distances that approximate to the spaced rulings on the wind grid. The other two pointers 17 and 18 similarly form a pair with edges so curved that their facing edges form radii from the pivot 15 and are identically graduated.

The overhang holds each pair of pointers down at their outer ends so that they cannot pass each other, and the pointers are graduated and numbered to represent the first digits of speeds or distances in units of ten miles each, counting the pivot 15 as zero. 10

The overhang 8 is shown as graduated uniformly so that when an even ten degree unit of the azimuth circle is set centrally (at the central mark on the overhang) each fifth successive unit on the overhang 8 is at the end of a connecting straight line drawn from the successive ten degree marking on the azimuth circle, with the result that the temporary position of a pointer 14, 20, 16, 17 or 18 may be temporarily identified by reading on the azimuth circle the number in degrees pointed out by the opposite end of its connecting straight line.

In the form shown the sine, and other trigonometrical functions, of any angle at the pivot 15, are proportionately equal to the functions of the angle subtended from the center of the wind grid.

The construction thus summarized enables a 30 pilot to rapidly find the flight course and the distance flown given, the true course and distance, and the force and direction of the wind.

For example, the true magnetic course being 100° from the magnetic meridian, ground distance 180 miles, the wind blowing 25 miles an hour at 45° , and the air speed of the airplane being 90 miles an hour, to find the course and distance to be flown, the azimuth circle 10 is rotated until one of the aliquot degree marks on the circle, say the degree mark 8 (standing for 80°) coincides with one of the continued lines 11 which join the outer semi-circle 12. The outer semi-circle 12 then becomes a field on which magnetic bearings will be indicated, because each continued line 11 joints some aliquot degree mark on the circle 10 to the outer semi-circle 12.

In Figure 1, this brings the azimuth circle or course mark 10 so that it is joined by a continued line to the graduation line A in the outer 50 semi-circle 12.

Then the wind grid 13 is rotated until the arrow on it points directly away from the wind direction.

Next the pointer 14 is swung on its pivot 15 to 65.

bring its arrow-head to the point A. Then pointer 16 on the same pivot 15 is swung until the graduation line "9" on it, representing a speed of 90 miles an hour, is at a ruled broken wind line which extends two and one-half spaces from the pointer 16 to the pointer 14 (these two and one-half spaces representing 25 miles per hour).

Now the arrow on pointer 16 shows the flight course to be steered, the directional reading being found by following the corresponding line 11 down to the number shown on the azimuth circle.

The air of flight distance also may be read by starting from the graduation 18 (representing 15 180 miles) on pointer 14 and following from this graduation 18 along the wind line on the wind grid to where the wind line intersects with pointer 16, giving a reading on the pointer 16 of 223 miles (the 22.3 actually read representing 223 20 miles). The angle between the pointers 14 and 16 representing the drift angle.

To solve another problem such as the double drift angle known as the "wind star" problem, four pointers are required. In this problem 25 the pilot is seeking to learn the direction and strength of the wind, based on the conditions assumed in the previous example.

For example, while steering a course of 86° off the magnetic north, the drift angle is observed 30 to be 14° to the right. On altering the course 26° into the wind (to the left) and steering a course of 60°, the drift angle is observed to be 6° to the right. Airspeed is known to be 90 miles per hour.

To find force and direction of the wind, the 35 azimuth circle is again set with "8" at the central perpendicular line. Pointer 16 is set to the first course 86°, read on the azimuth circle, as in the previous example, the pointer 14 is then set 14° to the right thereof which turns out to 40 be the point on the outer semi-circle 12 connected to the 100° (shown as 10) on the azimuth 10.

The pointer 17 is then set to the second course 60°, and the pointer 18 is set at an angle 6° to the right of pointer 17 or 66°. The wind grid 45 is then rotated until the length of the wind line between the pointers 14 and 16 is the same length as the wind line between pointers 17 and 18, starting in each case from the known airspeed 90 miles per hour, indicated on pointers 16 and 17.

The arrow on the wind grid then points toward 50 or away from the wind.

It will be noted that the built up body and disc and annular azimuth are each built of three layers 21, 22 and 23 of Celluloid and that the 55 pivot 15 and hubs of the pointers are covered by an overlying sheet 20 of Celluloid.

It will be seen that the overhang 8 and shield 20 are each spaced from the sheet or layer 21 by a layer 25 of Celluloid and that the edge 26 of the body 3 is smoothed off by a Celluloid cement filling 27 at the center, and that the shield 20 is bent down on each side of the pivot to be flat on the body 3 beyond the limit of swing of the pointers.

Having thus described one embodiment of the 65 invention what is claimed is:

1. A calculating device including a body, a ruled disc rotatable in the body, a graduated annular disc rotatable between the ruled disc and the body and supporting the ruled disc, and a pair of separately settable pointers pivoted outside the discs on the body and graduated to correspond with the rulings on the disc and adapted to swing eccentrically across the discs.

75 2. A calculating device including a body, a

ruled disc rotatable in the body, a graduated annular disc rotatable between the ruled disc and the body and supporting the ruled disc, a pair of separately settable pointers pivoted outside the discs on the body and graduated to correspond with the rulings on the disc and adapted to swing eccentrically across the discs, and a graduated arc across which the pointers swing connected by lines to coincide with the graduated spaces on the annular disc. 5

3. A calculating device including a body, a ruled disc rotatable in the body, a graduated annular disc rotatable between the ruled disc and the body and supporting the ruled disc, a pair of separately settable pointers pivoted outside the discs on the body and graduated to correspond with the rulings on the disc and adapted to swing eccentrically across the discs, and a second pair of pointers similarly graduated and pivoted to swing across another area of the discs. 10 15

4. A calculating device including a body, a ruled disc rotatable in the body, a graduated annular disc rotatable between the ruled disc and the body and supporting the ruled disc, a pivot in the body outside the discs, and a pair 25 of separately settable pointers pivoted on the pivot and having each a straight edge radial to the pivot and graduated to correspond with rulings on the disc and swinging eccentrically over it so that they point to graduations on the body. 30

5. A calculating device including a body, a ruled disc rotatable in the body, a graduated annular disc rotatable between the ruled disc and the body and supporting the ruled disc, a pivot in the body outside the discs, a pair of separately 35 settable pointers pivoted on the pivot and having each a straight edge radial to the pivot and graduated to correspond with rulings on the disc and swinging eccentrically over it so that they point to graduations on the body, and a second 40 pair of separately settable pointers each having a straight edge radial to the pivot and graduated to correspond with the rulings on the disc and pointing to graduations on the body.

6. A calculating device including a body, a 45 ruled disc rotatable in the body, a graduated annular disc rotatable between the ruled disc and the body and supporting the ruled disc, a pivot in the body outside the discs, a pair of separately settable pointers pivoted on the pivot 50 and having each a straight edge radial to the pivot and graduated to correspond with rulings on the disc and swinging eccentrically over it, and a graduated arc across which the pointers swing and having its graduations connected by 55 lines to coincide with the graduated spaces on the annular disc.

7. A calculating device including a body, a ruled disc rotatable in the body, a graduated annular disc rotatable between the ruled disc and the 60 body and supporting the ruled disc, a pivot in the body outside the discs, a pair of separately settable pointers pivoted on the pivot and having each a straight edge radial to the pivot and graduated to correspond with the rulings on the disc and swinging eccentrically over it, a second pair of 65 separately settable pointers each having a straight edge radial to the same pivot and graduated to correspond with the rulings on the disc, and a graduated arc across which the pointers 70 swing and having its graduations connected by lines to coincide with the graduated spaces on the annular disc.

8. A calculating device including a body, a ruled disc rotatable in the body, and ruled in squares, 75

5 a graduated annular disc rotatable between the ruled disc and the body and graduated in degrees and supporting the ruled disc, a pivot in the body outside the discs, and a pair of separately settable pointers pivoted on the pivot and having each a straight edge radial to the pivot and graduated to correspond with rulings on the disc and swinging eccentrically over it and pointing to 10 graduations on the body.

10 9. A calculating device including a body, a ruled disc rotatable in the body, and ruled in squares, a graduated annular disc rotatable between the ruled disc and the body and graduated in degrees and supporting the ruled disc, a pivot in the body outside the discs, a pair of separately settable pointers pivoted on the pivot and having each a straight edge radial to the pivot and graduated to correspond with rulings on the disc and swinging eccentrically over it and pointing to 15 graduations on the body, and a second pair of separately settable pointers each having a straight edge radial to the same pivot and gradu-

ated to correspond with the rulings on the disc and pointing to graduations on the body.

10 10. A calculating device including a body, a ruled disc rotatable in the body, and ruled in squares, a graduated annular disc rotatable between the ruled disc and the body and graduated in degrees and supporting the ruled disc, a pivot in the body outside the discs, a pair of pointers pivoted on the pivot and having each a straight edge radial to the pivot and graduated to correspond with rulings on the disc and swinging eccentrically over it, and a graduated arc across which the pointers swing connected by lines to coincide with the graduated spaces on the annular disc. 15

11. A calculator having a three layer body, a three layer annular degree measuring rotatable ring within the body, a three layer disc within the ring, pointers pivoted above the body, a shield overlying the base of the pointers, a Celluloid spacer for the shield, and a cement filler smoothing off the edge of the shield. 20
